Inventor

George T. Hadley
by Wm. F. Booth,
his Attorney.

UNITED STATES PATENT OFFICE.

GEORGE T. HADLEY, OF SAN FRANCISCO, CALIFORNIA, ASSIGNOR OF ONE-HALF TO MARTIN F. HRUBANIK, OF SAN FRANCISCO, CALIFORNIA.

SHOW-WINDOW.

No. 808,201.

Specification of Letters Patent.

Patented Dec. 26, 1905.

Application filed February 7, 1905. Serial No. 4,589.

To all whom it may concern:

Be it known that I, GEORGE T. HADLEY, a citizen of the United States, residing in the city and county of San Francisco, State of California, have invented certain new and useful Improvements in Show-Windows; and I do hereby declare the following to be a full, clear, and exact description of the same.

My invention relates to the class of show-windows. Its object is to avoid confusing reflections, which in the ordinary show-window prevent the observer from perfectly seeing the contents displayed.

As is well known, the glass of show-windows reflects the sky, the buildings on the opposite side of the street, and the pavement in so confusing a manner that the observer cannot see the window display unless he puts himself in a position to cast a shadow, and then he can see only those articles upon which his shadow falls. Thus only a small portion of the display can be seen and that even at considerable inconvenience.

To remedy this difficulty, my invention consists in a show-window, the glass pane of which is formed and arranged in a novel manner, as I shall now describe.

Referring to the accompanying drawings, Figure 1 is a perspective view of my improved show-window. Fig. 2 is a vertical sectional view of the same. Fig. 3 is a horizontal section of the same. Fig. 4 is a vertical sectional view showing a modification in the shape of the glass.

A represents the frame generally of the show-window, and B is the glass. This glass is a straight plane horizontally, as shown in Fig. 3. Vertically it is dished or concaved. This concavity, as shown in Fig. 4, may be a complete and continuous one, or, as shown in Fig. 2, it may be formed of a combination of a lower straight vertical plane and an upper vertical concavity. In Figs. 1 and 2 it will be seen that the lower portion of the glass (represented by b) is a straight plane vertically and extends in the casing of the show-window up to a suitable height, which may be varied in practice, though I should say, for example, that it should extend to about the line of sight of the ordinary observer. From the upper end of the straight portion b the glass is made concave, as indicated by the portion b', the concavity being to the outside

of the show-window. This upper portion prevents reflections from the sky, so that they do not confuse the vision in observing the contents of the window. In the form of pane shown in Fig. 4 the concavity is presented to the outside. Another feature of the glass pane is that it is so arranged that no portion of it shall lie to the inside of the vertical plane of its base. In whole or in part it extends outwardly from said plane. By such form and arrangement of the glass pane, confusing reflections are obviated and the vision is unobstructed.

Having thus described my invention, what I claim as new, and desire to secure by Letters Patent, is—

1. A show-window having its glass pane concaved vertically, the concaved face of the pane being presented to the outside of the window, and no part of said pane lying to the inside of the vertical plane of its base.

2. A show-window having its glass pane formed in a straight plane horizontally, and concaved vertically, the concaved face of the pane being presented to the outside of the window and no part of the pane lying to the inside of the vertical plane of its base.

3. A show-window having its glass pane formed with a lower portion straight in vertical plane and an upper portion concaved in vertical plane with its concaved face presented to the outside of the window.

4. A show-window having its glass pane formed with a lower portion straight in vertical plane and an upper portion concaved in vertical plane with its concaved face presented to the outside of the window, and projecting wholly outwardly from the vertical plane of the lower portion.

5. A show-window having its glass pane formed in a straight plane horizontally, said pane having a lower portion straight in vertical plane and an upper portion concaved in vertical plane with its concaved face presented to the outside of the window, and projecting wholly outwardly from the vertical plane of the lower portion.

In witness whereof I have hereunto set my hand.

GEORGE T. HADLEY.

In presence of—
J. COMPTON,
D. B. RICHARDS.
